Atty.

UNITED STATES PATENT OFFICE.

HARRISON V. APPLEY, OF UPPER LISLE, NEW YORK.

AXLE-BOX.

SPECIFICATION forming part of Letters Patent No. 271,764, dated February 6, 1883.

Application filed December 27, 1882. (No model.)

To all whom it may concern:

Be it known that I, H. V. APPLEY, of Upper Lisle, in the county of Broome and State of New York, have invented certain new and useful Improvements in Axle-Boxes and Hubs; and I do hereby declare the following to be a full, clear, and exact description of the invention, such as will enable others skilled in the art to which it pertains to make and use it, reference being had to the accompanying drawings, which form part of this specification.

My invention relates to an improvement in axle-boxes and hubs; and it consists, first, in a box which is adjustable back and forth in the hub by means of a bolt or other holding device which is passed through the hub into the box; second, in the combination of the axle with an expandible box which is placed over the spindle, suitable washers or clamping devices which are passed over the box, so as to adjust it to the exact size of the spindle, and an outer inclosing-box which is placed in the hub, all of which will be more fully described hereinafter.

The object of my invention is to provide, first, a box which can be adjusted in the hub of the wheel, so as to set the wheel farther in or out, as may be desired; and, second, in an expandible box which may be fitted to the spindle, no matter how much it may be worn.

Figure 1 is a vertical longitudinal section of my invention. Fig. 2 is a detached view of the expandible box and the contracting rings.

A represents the spindle of the axle, and B the inner expandible box, which is applied directly thereto. This box is made from an elastic piece of metal which is bent into the proper shape, and which has its edges separated far enough from each other to allow the box to be closed upon the spindle by means of the screw-washers, bands, or other contracting devices, D, which are slipped over its outer side. As fast as the spindle wears away these rings can be screwed inward upon the box, and thus tighten it upon the spindle. As the edges of this box do not meet, ample space is left for the lubricating-fluid which surrounds the box to flow in between the spindle and the box, and thus keep the spindle always perfectly lubricated. The washers or other devices

which are slipped over the outer side of this box are made of the same diameter and fit accurately inside of the outer box, H. As these washers fit accurately inside of the box, it does not matter in what position they may be placed upon the inner box, for they always fit the outer box and serve as the bearing-points for the hub of the wheel upon the spindle. The outer box, H, is closed at its outer end and provided with a suitable screw-thread at its inner end to screw upon the nut J, which catches behind a second nut, L, which is screwed or otherwise secured upon the axle. This nut J revolves with the box around the nut which is secured to the axle, and serves at the same time as a guard to the box against dust and dirt. This outer box has a number of perforations made through its side in a line with each other, and passing through the hub into one of these perforations is the screw-bolt N, which secures the hub and the box together. As there are a number of these holes, and as the bolt is the only means for securing the hub and the box together, the box may be adjusted back and forth in the hub for the purpose of setting the wheel either in or out, as may be found necessary. By removing this bolt at any time lubricating oil or fluid may be poured through the hub directly into the box, thus forming an easy means of lubricating the spindles without having to remove the wheels.

Having thus described my invention, I claim—

1. An expandible box which is applied to the spindle and held in place by means of rings or washers which are placed upon the outer side of the box, substantially as shown.

2. The combination of an expandible box, which is applied to the spindle and held in place thereon by means of washers, with an outer box inside of which the washers accurately fit, and which washers form the bearings for the wheel, substantially as described.

3. The combination of an outer perforated box with the hub in which it is placed, and means for connecting the box to the axle, and a bolt which is passed through the hub into the box, whereby the hub may be moved in and out upon the box, substantially as set forth.

4. The combination of an expansible box which is applied directly to the spindle, suitable washers for contracting the box upon the spindle, an outer perforated box, means for attaching the outer box to the axle, and a bolt which is passed through the hub for the purpose of connecting the hub and the outer box together, substantially as specified.

In testimony whereof I affix my signature in presence of two witnesses.

HARRISON V. APPLEY.
